US0D1062106S

(12) **United States Design Patent** (10) **Patent No.:** **US D1,062,106 S**
(45) **Date of Patent:** **** Feb. 11, 2025**

(54) **COLLAPSIBLE CONTAINER FOR ANIMAL WASTE**

(71) Applicant: **Tanjman Innovations, LLC**, Fort Lauderdale, FL (US)

(72) Inventor: **Gary M. Tatangelo**, Aptos, CA (US)

(73) Assignee: **Tanjman Innovations, LLC**, Fort Lauderdale, FL (US)

(**) Term: **15 Years**

(21) Appl. No.: **29/823,207**

(22) Filed: **Jan. 14, 2022**

(51) **LOC (15) Cl.** **30-11**

(52) **U.S. Cl.**

USPC **D30/161**

(58) **Field of Classification Search**

USPC D30/161, 162, 199

(57) **CLAIM**

The ornamental design for a collapsible container for animal waste as shown and described.

DESCRIPTION

FIG. 1 is a perspective view of the collapsible container for animal waste showing my new design;

FIG. 2 is a first side view thereof;

FIG. 3 is a second side view thereof;

FIG. 4 is a third side view thereof;

FIG. 5 is a fourth side view thereof;

FIG. 6 is a top view thereof;

FIG. 7 is a bottom view thereof;

FIG. 8 is a perspective view of the collapsible container for animal waste in a collapsed position;

FIG. 9 is an alternate perspective view of the collapsible container for animal waste in a collapsed position; and,

FIG. 10 is a perspective view of the collapsible container for animal waste in a partially collapsed position.

The broken lines in the drawing depict portions of the collapsible container for animal waste that form no part of the claimed design.

1 Claim, 10 Drawing Sheets
